(57) **CLAIM**

The ornamental design for a slipper, as shown and described.

DESCRIPTION

FIG. 1 is a front, right and top perspective view of a slipper showing my new design.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

Broken lines in the drawings depict stitching lines and form part of the claimed design, except for the broken lines in the cover part, which depict shoelaces and shoelace buckles and form no part of the claimed design.

1 Claim, 7 Drawing Sheets
